[57] **CLAIM**

The ornamental design for a multi-purpose hand tool, as shown and described.

DESCRIPTION

FIG. 1 is a top plan view of a multi-purpose hand tool embodying my new design, with the handles in the folded closed position, the bottom plan view being a mirror image thereof;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view of the multi-purpose hand tool with the handles in the folded open position, the bottom plan view being a mirror image thereof;

FIG. 7 is a left side elevational view thereof, the right side elevational view being a mirror image thereof;

FIG. 8 is a front elevational view thereof; and,

FIG. 9 is a rear elevational view thereof.
